COMBINED WINDOW SASH AND SCREEN

Joseph Tondora, Linden, N. J.

Application October 11, 1948, Serial No. 53,920

6 Claims. (Cl. 160—97)

1

This invention relates to a combined window sash and screen.

It is an object of this invention to provide a combined window sash and screen readily installed in cellar windows of residences as well as in other windows of some types of construction.

A further object is to provide a combined sash and screen which is especially suited for poultry houses, barns, and the like.

Another object is to provide a combined sash and screen which is rugged but of relatively simple construction whereby the benefits thereof may be brought to a greater number.

Other objects of the instant invention will become apparent in the course of the following specification.

In the accomplishment of these objectives, a window sash of any design but of a size and shape to fit within the front of a window frame is formed and hinged along the upper edge to the top of the window frame. A stop is placed along the bottom of the frame so that when the sash is in the frame it is flush with the outside surface portions of the frame. The screen is attached to the top of the sash at the back but with the plane thereof at an angle to the plane of the sash. Thus as the sash is rotated outwardly from the frame the screen is brought into position. A second screen covers the space between the bottom of the sash and screen so that both the sash and screen may be opened at any distance desired within the limits of the stop. Means are provided for maintaining the sash and screen in the desired position and means are also provided for sealing any discrepancies between the sash and frame when the sash is in the closed position.

The invention will appear more clearly from the following detailed description when taken in connection with the accompanying drawings showing by way of example a preferred embodiment of the inventive idea.

In the drawings:

Figure 1 is a front elevational view of the combined window sash and screen with the sash in closed position and constructed in accordance with the principles of this invention.

Figure 2 is a side elevational view of the window shown in Figure 1 but with the sash in open position and with a part of the frame broken away to show the complete unit.

Figure 3 is a sectional view along the line 3—3 of Figure 1.

Figure 4 is a fragmentary rear elevational view of the combined sash and screen shown in Figure 1.

Figure 5 is a sectional view along the line 5—5 of Figure 1, and enlarged.

Referring now in greater detail to the drawings in which like reference numerals indicate like parts, reference numeral 10 indicates the window

2

frame, 11 the sash frame, and 12 the window screen frame.

The window frame 10 is formed of the spaced parallel top member 13 and bottom member 14 and the spaced parallel side members 15 and 16 joined along corresponding ends in the usual manner and adapted to provide an opening in the wall of a building for the transmission of light and air.

The sash frame 11 is designed to be removably inserted within the window frame 10 along the outer periphery of the opening formed therein and is made with the spaced parallel top member 17 and bottom member 18 and the spaced parallel side members 19 and 20 which are joined along corresponding ends in any known manner. Within the sash frame 11 is a transparent member 21 for the transmission of light and which may be secured in the frame in the usual manner. Of course, more than one transparent member 21 may be used. The upper edge of the top member 17 of the sash frame 11 is rotatably mounted along the lower edge of the top member 13 of the window frame 10 by any known hinged means 22 which is secured to the respective members by the screen 23 or the like. In this way, the sash frame 11 may be rotated in and out of the window frame 10 within the limits of a stop 24 which is transversely secured along the top surface portion of the bottom member 14 of the window frame 11 but terminating short of the spaced parallel side members 15 and 16 to permit the movement of the end members 25 and 26 described later. The stop 24 is so positioned in back of the outer periphery of the window frame 10 that the outside surface portions of the spaced parallel members of the sash frame 11 are flush with similar surface portions of corresponding members of the window frame 10 when the sash frame 11 is in closed position. With the sash frame 11 thus mounted in the window frame 10 imperfections in construction may leave an opening between the corresponding members of the frames in the closed position which may be completely covered by a second frame 27. The second frame 27 may be made with integrally formed spaced parallel top and bottom members 28 and 29 and spaced parallel side members 30 and 31, the second frame 27 being secured to the outside surface portion of the sash frame 11 by the screws 32 or other means. Obviously, the second frame 27 may be other than integrally formed and other means may be used for closing any discrepancies between the corresponding members of the window frame 10 and the sash frame 11.

The window screen frame 12 is formed in a manner similar to the sash frame 11, that is with the spaced parallel top member 33 and bottom member 34 and spaced parallel side members 35 and 36 which may be joined along corresponding ends in a known manner. The outside surface

portion of the spaced top member 33 is attached to the inside surface portion of the spaced top member 17 of the sash frame 11 by the later described end members 25 and 26 or otherwise and in such a manner that the plane of the screen frame 12 is at an angle to the plane of the sash frame 11. Since the illustrated sash and screen is hung so that the screen frame 12 swings inwardly and upwardly, it becomes necessary to bevel the top surface portion of the spaced top member 33 downwardly in order that the sash frame 11 may be swung inwardly to close the window frame 10 and which is best seen in Figures 2 and 3. Over the opening formed by the screen frame 12, a screen member 37 is disposed which may have a second screen frame 38 integrally formed to which the screen member 37 is attached in any known manner and then removably held over the opening of the screen frame 12 by the upright members 39 and 40, the latter being removably attached to the screen frame 12 by the screws 41 or the like.

Thus formed, the sash frame 11 and the screen frame 12 when viewed from the side (Fig. 3) are substantially in the form of a triangle, the open ends of the triangle being closed by the previously mentioned end members 25 and 26 which are made from reasonably rigid material having an arcuate bottom edge and which are removably attached to the ends of the sash and screen frames 10 and 11 by the screws 42 or the like.

As thus far constituted, the sash frame 10 and screen frame 11 leave an opening at the bottom formed by the spaced bottom member 18 of the sash frame 11, the spaced bottom member 34 of the screen frame 12 and the arcuate bottom edges of the end members 25 and 26. When using the sash and screen in the fully closed position, no covering is necessary for this opening. However, since other than the fully opened position of either member has been found to be desirable under certain conditions, a second screen 43 is secured over the opening in any known manner but sufficiently removed from the base to permit rotating the unit over the top surface portion of the stop 24, the bottom edges of the end members 25 and 26 being designed to rotate between the inside surface portions of the opposed side members 15 and 16 of the window frame 10 and the corresponding ends of the stop 24. The second screen 43 may be of fine mesh in the manner of the screen 37 as a protection against insects or of larger mesh as a protection against rodents and the like.

To maintain the combined sash frame 11 and screen frame 12 in locked open or closed positions and to maintain said members in partially open and closed positions, a support 44 is mounted on the inside of one of the spaced parallel side members 15 or 16 of the window frame 10 to contact with a curved member 45 the base of which is attached to the outside surface portion of a corresponding spaced side member of the screen frame 12 by any suitable means 46 and in which a slot 46a is provided. A screw 47 is adjustably inserted through the support 44 and the aligned slot 46 and held in place by the wing nut 48 releasably securing the members together in any desired position of the combined sash and screen.

The operation of the combined sash and screen is as follows:

Assuming that the combined sash frame 11 and screen frame 12 are designed for a given window frame 10, that the light transmitting member

21 is inserted in the sash frame 11 and the screen member 37 in the screen frame 12, the combined unit is inserted in the front of the window frame 10 with the projecting edges of the second frame 5 27 over the outside surface portions of corresponding members of the window frame 10 and with the back surface portion of the spaced bottom member 18 of the sash frame 11 against the outside surface portion of the stop 24. The 10 hinged mounting means 22 is then attached along the upper edge of the spaced top member 28 of the sash frame 11 and the corresponding edge of the window frame 10. Thus mounted the combined unit may be swung outwardly until 15 the spaced bottom member 34 of the screen frame 11 is against the stop 24 to completely screen the window opening or inwardly to close the window opening with the sash and in which position the window opening is closed against 20 inclement weather. By tightening the thumb nut 48, the combined unit may be held in any desired position within the limits of design and with the window opening protected against intrusion by the second screen 43.

25 It is apparent that the specific illustration shown above has been given by way of illustration and not by way of limitation and that the structures above described are subject to wide variation and modification without departing 30 from the scope or intent of the invention, all of which variations and modifications are to be included within the scope of the present invention.

What is claimed is:

35 1. A window sash and screen in combination with a window frame adapted to be opened and closed by the sash and screen, means swingably mounting the top of the sash at the top of the frame and adapted to swing the same in and out 40 thereof, and means securing the top of the screen to the top of the sash and adapted to swing the screen out of the frame when the sash is swung therein and into the frame when the sash is swung out therefrom.

45 2. A window sash in combination with a window screen adapted to close the opening in a window frame when inserted therein, the sash comprising spaced parallel top and bottom members and side members, means securing said 50 members along corresponding ends, at least one light transmitting member for the spaced parallel members, means hingedly mounting the spaced top member of the sash to the top of the frame; the screen comprising spaced parallel top and bottom members and side members, means securing said members along corresponding ends, a screen member disposed over said spaced members, and means securing the spaced top member of the screen to the spaced top member of the 55 sash so constructed and arranged as to swing the screen out of the frame when the sash is swung therein and into the frame when the sash is swung out therefrom.

60 3. A window comprising a window frame, a sash for the window frame, and a screen for the window frame; the window frame comprising spaced parallel top and bottom and side members and adapted to provide an opening for the transmission of air and light, the sash comprising a sash frame and adapted to be removably inserted in the opening formed by the window frame, the sash frame comprising spaced parallel top and bottom members and side members, means securing said members along corresponding ends, at least one light transmitting mem-

ber disposed in the sash frame, means hingedly mounting the upper edge of the spaced top member of the sash frame to the lower edge of the spaced top member of the window frame and adapted to rotate the sash frame in and out of the window frame, the screen comprising a screen frame, the screen frame comprising spaced parallel top and bottom members and side members, a screen member disposed over the spaced members, means securing the spaced top member of the screen frame to the spaced top member of the sash frame and adapted to swing the screen out of the frame when the sash is swung therein and into the frame when the sash is swung out therefrom.

4. A window comprising a window frame, a sash for the window frame, and a screen for the window frame; the window frame comprising spaced parallel top and bottom and side members and means securing said members along corresponding ends, a stop transversely disposed on the top surface portion of the spaced bottom member; the sash comprising a sash frame, the sash frame comprising spaced parallel top and bottom and side members and adapted to be inserted within the periphery of the outer edge of the window frame with the outside surface portions of the spaced parallel members flush with corresponding surface portions of the window frame when the bottom member of the sash frame is against the stop on the spaced bottom member of the window frame, means securing said spaced members along corresponding ends, means hingedly securing the outside surface portion of the spaced top member of the sash frame to the corresponding surface portion of the window frame; the screen comprising a screen frame, the screen frame comprising spaced parallel top and bottom and side members and adapted to be inserted within the periphery of the inner edge of the window frame, means securing said spaced members along corresponding ends, a screen member disposed over the spaced members, means securing the spaced top member of the screen frame to the spaced top member of the sash frame and adapted to swing the screen out of the window frame when the sash is swung therein and into the frame when the sash is swung out therefrom.

5. A window comprising a window frame, a sash for the window frame, and a screen for the window frame; the window frame comprising spaced parallel top and bottom and side members and means securing said members along corresponding ends, a stop transversely disposed on the top surface portion of the spaced bottom member and adapted to leave a space between the spaced side members at either end; the sash comprising a sash frame, the sash frame comprising spaced parallel top and bottom and side members and adapted to be inserted within the periphery of the outer edge of the window frame with the outside surface portions of the spaced parallel members flush with corresponding surface portions of the window frame when the spaced bottom member of the sash frame is against the stop on the spaced bottom member of the window frame, means securing said spaced members along corresponding ends, at least one light transmitting member for the sash frame, means on the sash frame overlapping corresponding surface portions of the window frame when the sash frame is against the stop, means hing-

edly securing the upper edge of the spaced top member of the sash frame to the lower edge of the spaced top member of the window frame; the screen comprising a screen frame, the screen frame comprising spaced parallel top and bottom and side members and adapted to be inserted within the periphery of the inner edges of the window frame, means securing said spaced members along corresponding ends, a screen member disposed over the spaced members, means securing the spaced top member of the screen frame to the spaced top member of the sash frame at the back and adapted to rotate the screen in and out of the window frame and to close the same when against the stop, a reinforcing side member disposed on either side of the sash and screen frames, the bottom surface portion of the reinforcing members being arcuate and adapted to rotate with the sash and screen adjacent the inside surface portions of the spaced parallel side members of the window frame and the ends of the stop, and means releasably securing the window sash and window screen in position.

15 6. A window sash in combination with a window screen and adapted to open and close a window frame; the window sash comprising spaced parallel top and bottom members and adapted to be removably inserted within the outer periphery of the window frame means securing said members along corresponding ends, at least one light transmitting unit for the spaced members, a stop longitudinally disposed on the bottom of the window frame with a space between the sides of the frame and adapted to maintain 20 the outside surface portions of the sash and window frame flush when the spaced bottom member of the sash frame is against the stop, means securing the upper edge of the spaced top member of the sash frame to the lower edge of the

25 top of the window frame, a second frame disposed over the outside surface portions of the sash frame and adapted to cover the openings between corresponding members of the window frame when the sash frame is against the stop; the window screen comprising a screen frame, the screen frame comprising spaced parallel top and bottom and side members and adapted to be inserted within the periphery of the inner edges of the window frame, means securing said spaced members along corresponding ends, a screen member disposed over the spaced members, means securing the spaced top member of the screen frame to the spaced top member of the sash frame at the back and adapted to rotate the screen in and out of the window frame and to close the same when against the stop, a reinforcing side member disposed on either side of the sash and screen frames, the bottom edges of 30 35 40 45

50 55 60 65 the reinforcing members being arcuate and adapted to rotate with the sash and screen adjacent the inside surface portions of the sides of the window frame and the ends of the stop, a second screen member disposed in the base of the space formed by the sash and screen and reinforcing members and adapted to be rotated with said members adjacent the upper edge of the stop, and means releasably maintaining the window sash and window screen in position.
